[57] CLAIM

The ornamental design for an air freshener housing, as shown and described.

DESCRIPTION

FIG. 1 is a view in isometric showing the new air freshener housing design, on an enlarged scale;

FIG. 2 is a view in side elevation of the design shown in FIG. 1, all sides being identical, the broken line drawings of an air freshener fluid container and a bottom conductor are for illustrative purposes only and forms no part of the claimed design;

FIG. 3 is a top plan view with reference to FIG. 2; and, FIG. 4 is a bottom plan view with reference to FIG. 2.
